UNITED STATES PATENT OFFICE.

ABRAHAM SATZMAN, OF NEW YORK, N. Y., ASSIGNOR TO HENRIETTA BERNARD, OF FORT PLAIN, NEW YORK.

SAFETY COAL-CHUTE COVER.

1,330,012.

Specification of Letters Patent.

Patented Feb. 3, 1920.

Application filed December 20, 1918. Serial No. 267,652.

To all whom it may concern:

Be it known that I, ABRAHAM SATZMAN, a citizen of the United States, and a resident of the city of New York, borough of Bronx, in the county of Bronx and State of New York, have invented a new and Improved Safety Coal-Chute Cover, of which the following is a full, clear, and exact description.

10 This invention relates to covers for manholes, as for instance a cover for a coal chute, and has for an object the provision of an improved construction which embodies as its essential feature safety resulting from 15 a locking mechanism and associated parts for continually holding the cover near the chute and for locking the cover when closed.

Another object in view is to provide a 20 cover hinged to a casing and a spring pressed so that when it is unlocked it will automatically move to a partially opened position.

A further object more specifically is the 25 provision of a cover with a lock for holding the same positively closed, and means for opening the cover slightly when the lock has been moved to an unlocked position whereby the cover may be easily opened when desired and is positively held closed 30 after having been first moved to a closed position.

In the accompanying drawings:

Figure 1 is a longitudinal vertical section through a cover and associate parts embodying the invention, the same being taken on line 1—1 of Fig. 2.

Fig. 2 is a top plan view of the cover and frame shown in Fig. 1.

Fig. 3 is a fragmentary sectional view 40 showing a slight modified arrangement of spring.

Fig. 4 is a fragmentary bottom plan view showing a modified locking structure to that disclosed in Fig. 1.

45 Referring to the accompanying drawing by numerals, 1 indicates a pavement of any desired kind in which a chute 2 is arranged. Positioned at the surface, but fitting into the chute 2 is a casing 3 formed with an outwardly extending flange 4 and an inwardly extending flange 5. This casing and the cover 6 therefor is a manhole structure adapted for any purpose, but especially adapted for coal chutes. The section 7 of 50 the flange 5 is provided with upstanding ears 55

8 and 9 for receiving a pintle 10, said pintle also passing through the ear or knuckle on cover 6. The cover 6 is of a size to fit easily within the casing 3 as shown in Figs. 1 and 2, but to overlap the flange 5. In order to 60 positively hold the cover 6 closed a bolt 12 is provided which normally underlies the flange 5, said bolt being urged by spring 13 to this position. The bolt 12 is slidingly fitted into posts 14 and 15 secured to the 65 plate 16, said plate being in turn rigidly secured to the cover 6 by screws or in any desired manner. A pin 17 extends through the bolt 12 and is provided with an eye 18 for receiving the end of a chain or cable 19. 70 Spring 13 presses against the post 14 and against the pin 17 in order to hold the parts normally as shown in Fig. 1. When the chain 19 is pulled bolt 12 will be moved from beneath the flange 5 against the action 75 of spring 13. This will release cover 6 so that the same will rise to the dotted position shown in Fig. 1 under the action of springs 20 and 21. These springs are rigidly secured to the flange 5 and extend 80 through notches or recesses 22 and 23. It will, of course, be understood that the person operating the chain will be in the coal pit or at some convenient place within the house or cellar. However, after the bolt 12 85 has been released and the parts moved to the dotted position shown in Fig. 1 any one on the pavement may raise the cover 6 to a full open position in order that the coal or other articles may be dumped into the 90 chute 2. It will be noted that the cover 6 is hinged to the section 7 of frame 3, this will prevent any accidental loss of the cover so that when the coal has been properly stowed away the bolt 12 will snap into its locked 95 position as shown in Fig. 1. Preferably the ends of pintle 10 are riveted or upset so as to prevent the removal of the cover.

In Fig. 3 a modified structure is disclosed in which a spring 24 is secured at 25 to the 100 cover 6 so that the free end 26 of the spring may press against the casing or frame 3 in the corner 27. This arrangement will allow the cover to raise automatically when released and also permit the cover to be 105 opened wide manually.

In Fig. 4 a modified form of catch is shown in which the bolt 28 is pivotally mounted at 29 so as to be swung back and forth by the chains 30 and 31 connected to 110

the extensions 32 and 33 of the bolt. A guide or keeper 34 is provided held in place by screws or other means 35 and 36 which act as stops for limiting the swinging movement of the bolt 28. When the parts are in the position shown in Fig. 4 the bolt is in a locked position, but upon pulling the chain 31 the bolt will be swung out of engagement with the flange 5 whereupon the cover 6 may be automatically moved upwardly under the action of springs 20 and 21. After the cover has been closed a reverse movement will naturally bring the parts to a locked position.

15 What I claim is:

1. A safety coal chute cover comprising an annular casing having an annular flange offset from the top, said flange having a square section provided with a pair of upward standing ears acting as knuckles of a hinge, a lid provided with an opposite extension acting as a knuckle of a hinge, a pintle extending through all of said knuckles for pivotally connecting said lid with said

flange, a spring acting on said lid for automatically raising the same, and a catch for locking said lid closed.

2. A safety coal chute comprising an annular casing formed with an inwardly extending annular flange offset from the top and with a pair of hinge knuckles, said annular casing having substantially oppositely positioned cut away portions therein, a circular lid adapted to rest on said annular flange, said lid being formed with a hinge knuckle, a pintle extending through said hinge knuckle on the lid and the hinge knuckles on the casing for pivotally connecting the lid with the casing, a lock for normally holding the casing closely in contact with said annular flange, a spring member for each of the notches in said flange, each of said spring members being secured to the flange and projecting therethrough so as to press continually against the lid when closed in order to open the lid when said lock is unlocked.

ABRAHAM SATZMAN.
